UNITED STATES PATENT OFFICE.

JOHN FOSTER STEPHENSON, OF GLENFERRIE, VICTORIA, AUSTRALIA, ASSIGNOR TO
GEORGE TAYLOR MUIR, THOMAS McLEOD MUIR, AND JAMES KENNEDY MUIR, JNR., TRADING AS FIRM OF J. & T. MUIR, OF NORTH MELBOURNE, AUSTRALIA.

DESIGN FOR A BEDSTEAD END.

No. 40,109.

Specification for Design.

Patented June 29, 1909.

Application filed January 21, 1909. Serial No. 473,581. Term of patent 14 years.

To all whom it may concern:

Be it known that I, JOHN FOSTER STEPHENSON, a subject of the King of Great Britain, residing at Haines street, Glenferrie, in the State of Victoria, Australia, have invented a new, original, and ornamental Design for a Bedstead End, of which the following is a specification, reference being had to the accompanying drawing, forming part thereof.

The figure is an elevation of a bedstead end, showing my new design.

I claim:

The ornamental design for a bedstead end as shown.

JOHN FOSTER STEPHENSON.
